SHOCK ABSORBER AND STABILIZER

Charles H. Dolan, II, Old Greenwich, Conn.

Application February 9, 1945, Serial No. 576,993

2 Claims. (Cl. 105—164)

1

My invention relates to shock absorbers and stabilizers for vehicles and has particular reference to elastic suspension systems in which a liquid and compressed air are employed for suppressing shocks and for stabilizing vehicles and, more particularly, railroad cars in their movement over the rails.

One of the main objects of my invention is to provide means to dampen or to absorb the vertical shocks caused by the unevenness of the rail joiners and the rails themselves. I provide for this purpose shock absorbers in the form of hydraulic cylinders with pistons, the liquid in the cylinders being under pressure from compressed air in a separate vessel, communicating with the hydraulic cylinder. The combination of hydraulic frictional or viscous resistance with the elastic resistance of the compressed air affords a more effective suppression of the shocks and improved riding qualities of the railroad cars and other vehicles.

Another object of my invention is to provide means to stabilize the railroad cars on the curves thereby making it possible for the cars to attain greater speed in passing over the curves than it is possible with conventional types of suspension. At the same time, such stabilization affords a greater comfort to the passengers.

Such a stabilization on the curves is effected in my system by providing an air valve, controlled by a pendulum or by a device similar to a bank indicator used on airplanes. The air valve is so connected to the air cylinders of the shock absorbers as to increase the air pressure for the cylinder or cylinders at the side of the car which rides over the outer rails on a curve, thereby causing this side of the car to rise. The body of the car is thereby "banked" on the turns or inclined in a direction toward the center of the curve, thereby greatly increasing the stability of the car on the curves. The banking or inclination of the car is automatically controlled by the bank indicator or pendulum, being greater for higher speeds.

My invention is more fully described in the accompanying specification and drawings in which—

Fig. 1 is a fragmentary transverse sectional view of a railroad car showing the arrangement of my shock absorbers and stabilizers;

Fig. 1A is a fractional detail view of an air valve on an enlarged scale;

Fig. 2 is a fragmentary perspective view of a railroad car chassis with my shock absorbers and stabilizers.

2

My shock absorber and stabilizer as shown in Figs. 1, 1A and 2 consists of hydraulic cylinders 1, mounted vertically on suitably formed depressed portions of frames 3, 4 of a car, truck or chassis 5 for wheels 2. The cylinders are closed at both ends, the top cover 6 having a hole with a packing gland 7 for the rod 8 of a piston 9. The upper ends of the rods have ball-shaped enlargements 10, rotatively held between lower and upper halves 15, 16 respectively of bearings supported on the under side of arcuate beams 17, 18 concentric with the axis of rotation of the end portion of the car body 19 on a vertical shaft 20 extending from the central portion of the truck 5. The body of the car is slidably supported on the curved tracks, permitting a certain amount of rotation on the curves in a horizontal plane. The end portion of the car body is thereby supported at all times on four hydraulic pistons 9, moving in the hydraulic cylinders 1. Buffer springs 22, 23 are provided in the end portions of the cylinders for suppressing shocks when the piston moves all the way up or down in the cylinder. The bottom of each cylinder is connected by 10 a pipe 24 with the bottom of a corresponding oil and compressed air accumulator 25, the upper end of the accumulator being connected by a pipe 26 with ports 27, 28, 29, 30 of a casing 32 of a slide valve 32'. Two middle ports 33, 34 are connected by 15 a pipe 35 with a storage tank 36 for compressed air. The tank is supplied with the compressed air through a pipe 31 from an ordinary air compressor (not shown) provided for the air brakes. The slide valve 32' is provided with two connecting ducts 38, 39 and open ports 40, 41. The slide valve is pivotally connected with the ball-shaped upper end 42 of a pendulum 43, pivotally supported at 44 and provided with a weight 45 at the lower end. 20 The pendulum is deflected by inertia, particularly when the car is rounding a curve on rails 21. As shown in Fig. 1, if the car moves to the left on a curve, the pendulum is deflected by inertia to the right. As a result, the upper end of the pendulum shifts the valve 32' to be moved to the left, causing the valve to establish a connection between the upper portion of the left air cylinder or accumulator 25 and the outside air by the duct 27 registering with the open port 40, thereby releasing the air pressure in the left accumulator 25. At the same time, the compressed air supply pipe 35 will be connected by a duct 39 with the duct 30, leading to the upper portion of the right accumulator 25, thereby applying the air pressure to the upper portion of the accumulator and to a floating

piston 48, driving the oil 49 from the accumulator through the pipe 24 to the bottom of the right cylinder 25. As a result, the right side of the car will be raised as shown, giving the car the proper banking inclination to overcome the centrifugal force, which otherwise would tend to turn the car over to the right, i. e. in the direction of the centrifugal force. A pressure equalizing pipe 37 connects the upper portions of the cylinders 1 for allowing the air to be moved from one cylinder to the other. Such a banking position of the car also tends to distribute the pressure on the wheels more evenly, making it possible to run the car at a higher speed on the curves, with greater safety and comfort for the passengers, as well as with reduced wear on the outer rails on the curves.

The stabilizing cylinders 1 also function as shock absorbers, damping the shocks transmitted to the body from the wheels through the medium of a viscous liquid 49 in the cylinders, the shocks being further cushioned by the application of the compressed air to the liquid. The floating pistons 48 prevent splashing of the liquid and formation of an air emulsion. The size of the cylinders is preferably so selected that with a given air pressure per square inch, the pistons should exert a lifting force on the sides of the car, exceeding their static weight. The load of the body may be distributed on several cylinders along each side of the chassis.

Shoulders 20' on the post 20, engaging the edges of a body floor 51, limit the upward movement of the body 19.

The swaying movement of the car on the curves and when caused by irregularities of the track is further damped by the provision of angularly positioned shock absorbers consisting of hydraulic cylinders 52, 53, pivotally attached at 54, 55 to the sides of the car body 19. Plungers 56, 57 are slidably fitted in the cylinders and are connected to the outer ends of rods 58, 59, the other ends of the rods being connected to forks 60, 61 pivotally connected to a central post 20 at 63 at a point above the center of lateral rotation of the body 19. The pistons are hollow inside and are in communication with the space in the cylinders by ports 64, 64' for allowing the oil 62 to flow back and forth in the cylinders past the pistons when the pistons are moved by the swaying of the car body. The hydraulic shock absorbers stabilize such swaying movements in a manner similar to the stabilization of the airplane when landing on its wheels when the wheels are provided with hydraulic shock absorbers.

My hydraulic shock absorbers are also applicable to the damping of the longitudinal shocks as may be caused by sudden starting of the locomotive or sharp changes in the locomotive pull. Such an arrangement is shown in Fig. 2 showing the chassis of a railroad car 19. A drawbar 63 is slidably supported on the chassis with a coupling 72 and can freely move longitudinally. The rear end of the drawbar is pivotally connected with a plunger in a hydraulic cylinder 83. The outer end of the cylinder 83 is pivoted to a stationary bracket 85 attached to the chassis.

While the invention has been described in detail with respect to certain particular preferred examples, it will be understood by those skilled in the art after understanding the invention, that various changes and further modifications may be made without departing from the spirit and scope of the invention, and it is intended therefore in the appended claims to cover all such changes and modifications.

10. What is claimed as new and desired to be secured by Letters Patent is:

1. In a vehicle having a chassis with wheels and a body movably supported on the chassis, the combination of a shock absorbing and stabilizing device comprising a pair of hydraulic cylinders with pistons, each cylinder with its piston being interposed between one side of the chassis and a corresponding side of the body; an accumulator for each cylinder, the lower portion of the accumulator being in communication with the cylinder under the piston and arranged to contain the excess of a liquid filling the cylinder under the piston; means to admit a compressed elastic fluid into the accumulators for moving the pistons outwards in the cylinder thereby causing the pistons to support the weight of the respective sides of the body; and means to control the admittance of the compressed fluid independently in each accumulator for causing the body to bank when the vehicle is moving over a curved path.

2. In a vehicle having a chassis with wheels and a body movably supported on the chassis, the combination of a shock absorbing and stabilizing device comprising a pair of hydraulic cylinders with pistons, each cylinder with its piston being interposed between one side of the chassis and a corresponding side of the body; an accumulator for each cylinder, the lower portion of the accumulator being in communication with the cylinder under the piston and arranged to contain the excess of a liquid filling the cylinder under the piston; valve means for selectively admitting a compressed elastic fluid in one or the other accumulator for causing the piston in the corresponding cylinder to be moved outwards; and pendulum means responsive to the laterally acting centrifugal force produced by the vehicle rounding a curve, the pendulum means being operatively connected with the valve means for causing the body to be banked in opposition to the effect of the centrifugal force.
